[57] CLAIM

The ornamental design for a combined fork and chopstick, substantially as shown and described.

DESCRIPTION

FIG. 1 is a side view of a combined fork and chopstick showing my new design; the opposite side of the combined fork and chopstick being a mirror image thereof; FIG. 2 is a view taken thereof along line 2—2 of FIG. 1 looking in the direction indicated by the arrows, the opposite side of said combined fork and chopstick being a mirror image of FIG. 2;

FIG. 3 is an end view thereof;

FIG. 4 is a view of the opposite end thereof;

FIG. 5 is a sectional view taken through the combined fork and chopstick along line 5—5 of FIG. 1;

FIG. 6 is a sectional view taken through the combined fork and chopstick along line 6—6 of FIG. 1; and

FIG. 7 is a sectional view thereof taken along line 7—7 of FIG. 1.
